DESIGN FOR A TEXTILE FABRIC OR SIMILAR ARTICLE

Joseph C. Sibal, Glendale, Long Island, N. Y., assignor to Yale Fabrics Corp., New York,
N. Y.

Application May 22, 1937, Serial No. 69,495

Term of patent 3½ years

To all whom it may concern:

Be it known that I, Joseph C. Sibal, a citizen of the United States, residing at 7121 71st Place, Glendale, Long Island, New York, have invented a new, original, and ornamental Design for a Textile Fabric or Similar Article, of which the following is a specification, reference being had to the accompanying drawing, forming a part thereof.

The figure is a plan view of a textile fabric showing my new design. The dot and dash lines on the drawing show the design unit, which unit is repeated in staggered succession, as indicated by the angles A and A'.

I claim:

The ornamental design for a textile fabric or similar article as shown and described.

JOSEPH C. SIBAL.
